Patented Mar. 7, 1916.

UNITED STATES PATENT OFFICE.

BENJAMIN F. GETZ, OF MECHANICSBURG, PENNSYLVANIA.

COLLAR FOR EQUINE ANIMALS.

1,174,140.

Specification of Letters Patent.

Patented Mar. 7, 1916.

Application filed September 15, 1915. Serial No. 50,858.

To all whom it may concern:

Be it known that I, BENJAMIN F. GETZ, a citizen of the United States, residing at Mechanicsburg, in the county of Cumberland and State of Pennsylvania, have invented certain new and useful Improvements in Collars for Equine Animals, of which the following is a specification, reference being had to the accompanying drawings.

10 This invention relates to certain improvements in collars for equine animals; and it is an object of the invention to provide a device of this general character having novel and improved construction whereby the 15 same possesses a minimum of weight and whereby the collar is effectively protected against wear incident to the harness coacting therewith.

The invention consists in the details of 20 construction and in the combination and arrangement of the several parts of my improved collar whereby certain important advantages are attained and the device is rendered simpler, less expensive and otherwise 25 more convenient and advantageous for use, all as will be hereinafter more fully set forth.

The novel features of the invention will be carefully defined in the appended claim.

30 In order that my invention may be the better understood, I will now proceed to describe the same with reference to the accompanying drawings, wherein—

Figure 1 is a view in side elevation of 35 the device as herein disclosed; Fig. 2 is a sectional view taken substantially on the line 3—3 of Fig. 1; and Fig. 3 is a sectional view taken substantially on the line 4—4 of Fig. 1.

40 As disclosed in the accompanying drawings, C denotes my improved collar as an entirety and herein disclosed as split at its upper end and coacting with said split end are the fastening means M of any desired 45 construction.

1 denotes the rim or fore-wale of the collar and 2 the back or after-wale and, as herein disclosed, the fore-wale 1 and after-wale 2 each comprises a casing 3 of textile 50 fabric, preferably canvas, and a suitable filler F preferably of straw, and the fore-wale 1 and after-wale 2 are operatively connected in a conventional manner. The fore-wale and after-wale are separately packed 55 and, as herein embodied, the casing 3 of the back or after-wale 2 is effectively formed

upon its filler F by the lacing L disposed around the outer margin thereof.

In order to protect the collar against wear incident to the hames when applied thereto, 60 I find it of particular advantage to provide the outer face of the after-wale adjacent the fore-wale with the lamination or liner 4 of leather or other material possessing the requisite resistive qualifications and said 65 lamination or liner 4 at the upper end of the collar extends entirely across the outer face of the back or after-wale 2 so as to afford a protection against the driving lines which pass over the collar at this point. The 70 major portion of the lamination or liner 4 is of a width less than the width of the forward face of the after-wale, said width being sufficient, however, to have the hames when applied to the collar contact therewith. 75 The outer faces of the after-wale or back 2 at the shoulders or crooks thereof are provided with the supplemental laminations or liners 5 of leather or the like which overlie the adjacent portion of the lamination or 80 liner 4 and extend entirely across said outer faces and serve as a protection against the harness connection with the hames.

The top or sweeny portion of the rim or fore-wale is incased with a lamination or 85 liner 6 also of leather to protect said fore-wale or rim against the wear incident to that portion of the collar and the throat portions of the fore-wale and after-wale are incased with the laminations or liners 7 and 8, respectively, of leather or the like, said last named liners protecting the collar against the throat strap.

90 From the foregoing description, it is thought to be obvious that a collar constructed in accordance with my invention is of an extremely simple and comparatively inexpensive nature and is particularly well adapted for use by reason of the convenience and facility with which it may be assembled, 95 and it will also be obvious that my invention is susceptible of some change and modification without material departure from the principles and spirit and for this reason I do not wish to be understood as limiting myself to the precise arrangement and formation of the several parts herein shown in carrying out my invention in practice.

I claim:

110 As a new article of manufacture, a collar for equine animals comprising a fore-wale and an after-wale, stitching connecting the

fore-wale and after-wale, the outer face of the after-wale having a liner of leather adjacent its connection with the fore-wale and extending entirely therearound, the upper portion of the liner being extended entirely across the outer face of the after-wale, the remaining portion of the liner being of a width less than the width of the outer face of the after-wale, additional liners disposed entirely across the outer face of the after-wale at the shoulders thereof and overlying the adjacent portions of the first named

liner, and liners incasing the throat portions of the fore-wale and the after-wale, the stitching connecting the fore-wale and after-wale being directed through the forward margins of the first two named liners. 13

In testimony whereof I hereunto affix my signature in the presence of two witnesses.

BENJAMIN F. GETZ.

Witnesses:

GEORGE BAISH,
W. O. NEIDIG.
